(Cl. D15—8)

FIG.1

FIG.2

FIG.3

Fig. 1 is a side elevation of a portable seat, showing my new design.

Fig. 2 is a rear elevation of the seat.

Fig. 3 is a top plan view of the seat.

My design for a portable seat comprised of seat and back elements combined as shown is characterized by the specific configuration of said elements together with the specific matching decorative detail in the center of each element.

I claim:

The ornamental design for a portable seat, substantially as shown and described.
